ABSTRACT OF THE DISCLOSURE

The present invention relates to a new textile yarn package of textile yarn wound on a rigid central support and a process for producing said package, more especially superposed yarns, e.g. man-made ones, arranged on a central support, e.g. bobbin, cone, pirn or cop, placed in a gas-tight plastic bag in which the pressure is below atmospheric, whereby handling and transport are facilitated.

BACKGROUND OF INVENTION

The principal form of wound arrangement of textile yarns consists of superimposed layers of yarns arranged parallel to one another on a rigid central support. These wound arrangements are known under various names, depending on the form of the central support and on the method of winding: pineapple, cylindrical bobbin, double-tapered cylindrical bobbin, cone, single-flange bobbin, cigarette, pirn or cop, and which are hereinafter referred to by the single term "bobbin" for the sake of simplicity.

In the case of man-made fibres, especially synthetic ones, in order to obtain a satisfactory winding on the support, it has been proposed previously to wind successive layers of coils of yarn at a tension which does not appreciably exceed that of internal layers. This type of fairly slack winding nevertheless provides bobbins of fairly low compressibility and on the one hand allows the yarn to relax, which is advantageous in the case of synthetic fibres, especially polyester yarns, which always have a slight tendency to contract or even have to be made to contract and on the other hand facilitates unwinding and prevents the well-known fault of surge of reeling in weaving (i.e. formation of stripes due to variations in yarn tension). The coils, however, suffer from an undesirable tendency to sloughing such that the slightest shock will cause the package to collapse and become unserviceable. For the last mentioned reason, it is essential to transport these packages in special containers which are bulky and very expensive since they are generally used only once. A particularly suitable container is described in French Patent No. 1,004,725 which is entitled "Containers for articles having an axial cavity, especially supports for textile yarns."

Preservation in a partial vacuum to protect substances from adverse influence of the atmosphere is a widespread technique, especially in the food industry. Briefly, this technique consists in placing the materials to be protected in a satchel formed of a flexible film of a suitable plastic material, reducing the pressure inside the satchel below atmospheric pressure and finally sealing said satchel by any appropriate means.

It has been proposed previously to keep in a partial vacuum certain textile materials to be preserved. For example, in order to maintain a certain degree of humidity in the yarn bobbins, especially those with artificial yarns, it has been proposed to place said bobbins in a rigid, i.e.

2

non-deformable, container and then produce a partial vacuum within said container. This method of preservation obviously does not provide a solution of the problem, i.e. to improve the packaging under shock and during transport of the above bobbins, since these are free to move within their container.

It has also been suggested previously to pack under vacuum inside flexible plastic bags textile materials of high compressibility such as balls of knitting yarn. This process has essentially the effect of facilitating the storage of textile materials of low density but which are particularly bulky by appreciably reducing the apparent volume of said textile materials. Thus, when the ball of yarn is required for use, the bag is opened and the highly compressed material recovers its initial shape.

This method of preservation has not hitherto been proposed for application to the storage of textile yarns wound on a central support, using for this purpose flexible and deformable envelopes which will conform closely to the shape of these wound arrangements after evacuation.

The problem to be solved by the present invention is to provide a simple but effective means of economically and effectively preserving textile windings with a central rigid support.

I have now found that this problem can be solved by placing the above wound arrangements of textile yarn in a flexible bag of suitable shape made from a gas-tight plastic material, setting up a pressure below atmospheric pressure inside said bag and sealing it.

SUMMARY OF INVENTION

The present invention thus provides a process for the production of a package of textile yarn, which comprises placing a wound arrangement of superposed layers of the textile yarn arranged parallel to one another on a rigid central yarn support in a flexible gas-tight envelope of plastic material, reducing the pressure inside said envelope below atmospheric pressure and closing said envelope so that the inside of it is below atmospheric pressure.

The present invention also provides a package of textile yarn consisting of superposed yarn layers arranged parallel to one another on a rigid centrally disposed yarn support surrounded by a flexible gas-tight envelope of plastic material, the pressure inside said envelope being below atmospheric pressure.

BRIEF DESCRIPTION OF THE DRAWING

In the accompanying diagrammatic drawing the only figure represents a cross section through a package of the invention in front elevation.

Unlike known methods, preservation in a partial vacuum of wound arrangements in the form of bobbins in accordance with the present invention has the essential function of imparting sufficient cohesion to the various layers of yarn, without, however, either disorganizing the relative arrangement of each of these layers, or modifying appreciably the apparent volume of said wound arrangements. The simple solution provided by the present invention has the effect of preventing layers of yarns sloughing and thus rendering possible the successful storage and transport of wound arrangements of low compressibility, an effect which could not be anticipated a priori.

As will be shown hereinafter, textile yarn packages in accordance with the invention can be conveyed without any particular precaution, and especially without risk of deterioration, while otherwise possessing the advantages

of conventional wound arrangements. In carrying out the invention, recourse may be had to the same basic techniques as in the food industry. In order to produce a vacuum, bell or suction teat machine may be used, the envelope may be closed either by applying fasteners or by welding. Manual or automatic techniques may be used, depending on the material or equipment available. Machines which extrude a gas-tight film directly round the wound arrangement may equally well be used, followed by creation of a vacuum and immediate closure to form the envelope.

The envelope of plastic material in the process of the present invention may be made of any of the packaging films currently used in the food industry, for example polyamide films, polyvinyl chloride films, polyvinylidene chloride films, polyester films, polyolefin (e.g. polyethylene) films and the like.

DESCRIPTION OF PREFERRED EMBODIMENTS

The manner in which the invention can be carried out and the advantages which result will be seen from the following examples.

Example 1

By means of a conventional frame, a sized polyethylene terephthalate yarn 1, of 65 denier/33 filaments and 1250 S t.p.m., is placed by cross-winding on a deformable cylindrical card support 2 of approximately 55 mm. diameter. (Winding tension 2 grammes). The resulting double-tapered cylindrical bobbin 3 contains 900 g. of yarn. (This is a bobbin currently used for the manufacture of curtain voiles). The yarn is shrunk by steaming for approximately 60 minutes at 130° C. which produces a degree of contraction of yarn on the bobbin of approximately 11%. The diameter of the bobbin is 12.5 cm.

This bobbin is then placed in a polyvinyl chloride envelope 4 which is closed on three sides, taking care to fold one portion 5 of the envelope into the interior of the card cylinder 2 at one end only. The thickness of the polyvinyl chloride envelope may be from 0.05 to 0.15 mm.

By means of conventional vacuum equipment, the pressure within the bag is reduced to 660 mm. of mercury and the fourth side of said bag is then heat-welded to produce seam 6.

Following this operation, no distillation of the size deposited to the yarn is observed.

The resulting bobbin is compact and has appreciably the same dimensions as before it is sealed in the evacuated envelope.

In order to demonstrate the advantages of the present invention the following tests were carried out:

(a) With the package produced as in the above example (designated as bobbin A), and

(b) With another bobbin (designated as bobbin B) produced in the same way as bobbin A, but without packaging according to the present invention.

(i) *Impact strength*.—This is evaluated by taking each bobbin in its axis which is at right angles to the floor, and allowing it to drop on to the floor from a height of approximately one metre; this characteristic illustrates the resistance to deformation and also the ease of transport, handling and storage of the bobbins.

(ii) *Unwinding tension*.—This is measured by means of the Rottschild Tensotron.

(iii) *Number of breaks*.—The number of breaks is measured per unit weight of unwound yarn.

(iv) *Surge of reeling*.—4 shaft armure satin fabric is woven with acetate yarns in the warp (this warp consisting of alternating black and white sections) and the yarns to be tested in the weft; stripes appearing in the fabric are evaluated visually.

	Bobbin	Impact strength ¹	Unwinding tension ²	Number of breaks per kg. ²	Surge of reeling ²
5	A-----	Good, no sloughing.	Substantially constant.	Nil-----	No stripes.
	B-----	Sloughing...	Substantially constant, differing little from that of (A).	Nil-----	Do.

¹ Test performed with bobbin A in the closed envelope.

² Before using the bobbin A, one side of the envelope is cut and atmospheric pressure allowed to be restored for at least five minutes.

10

Each of the above tests was carried out with five bobbins of type A and five bobbins of type B.

Example 2

15 The vacuum envelope of polyvinyl chloride is produced as in Examples 1, but this time using a cross-wound arrangement on a deformable card support of 36 mm. diameter, containing approximately 1 kg. of bright cellulose acetate yarn, 100 denier/18 filaments, twisted to 1200 twists per metre (bobbin for voiles).

After wet-steaming, the diameter of the bobbin is approximately 120 mm.

20 A compact package is obtained which is very resistant to impact, but has the same properties (unwinding tension, number of breaks per kilogramme and surge of reeling) as those of a similar bobbin which has not been sealed in an evacuated envelope in accordance with the invention.

25 Although the present invention is described herein with particular reference to specific details, it is not intended that such details shall be regarded as limitations upon the scope of the invention except insofar as included in the accompanying claims.

I claim:

30 1. A process for the production of a package of textile yarn, which comprises placing a fairly slack wound arrangement of superposed layers of textile yarn arranged parallel to one another on a rigid central yarn support in a flexible gas-tight envelope of plastic material, reducing the pressure inside said envelope below atmospheric pressure and closing said envelope so that the inside of it is below atmospheric pressure.

35 2. A package of textile yarn consisting of fairly slack superposed yarn layers arranged parallel to one another on a rigid centrally disposed yarn support surrounded by a flexible gas-tight envelope of plastic material, the pressure inside said envelope being below atmospheric pressure.

40 3. A package according to claim 2, in which the yarn is man-made.

45 4. The process as claimed in claim 1 wherein successive layers of coils of said yarn are at a tension which does not appreciably exceed that of internal layers.

50 5. The package as claimed in claim 2 wherein successive layers of coils of said yarn are at a tension which does not appreciably exceed that of internal layers.

55 6. The process as claimed in claim 1 wherein the pressure inside said envelope is reduced to below about 660 mm. of mercury.

60 7. The process as claimed in claim 1 wherein said envelope is closed by heat welding.
